UNITED STATES PATENT OFFICE.

ISIDOR MENDEL AND JOSEPH J. SMITH, OF CINCINNATI, OHIO, ASSIGNEES TO ISIDOR MENDEL, OF CINCINNATI, OHIO.

DISPLAY ATTACHMENT FOR SAMPLE-TRUNKS.

No. 906,050.

Specification of Letters Patent.

Patented Dec. 8, 1908.

Application filed February 19, 1908. Serial No. 416,655.

To all whom it may concern:

Be it known that we, ISIDOR MENDEL and JOSEPH J. SMITH, citizens of the United States, and residents of Cincinnati, Hamilton County, State of Ohio, have invented a certain new and useful Display Attachment for Sample-Trunks; and we do declare the following to be a clear, full, and exact description of the invention, attention being called 10 to the accompanying drawing, with the reference characters marked thereon, which form also a part of this specification.

This invention relates to a display-attachment for trunks, particularly such as are used 15 for carrying samples. It is shown as applied to a trunk of the ward-robe type used for carrying samples of clothing, and serves as a means upon which these samples may be advantageously displayed in proper position to 20 enable inspection by prospective buyers.

The invention consists of the particular construction of this device and of its particular connection to such a trunk.

In the following specification and particularly pointed out in the claims at the end thereof, will be found a full description of our invention, together with its manner of use, parts and construction, which latter is also illustrated in the accompanying drawing, in which:

Figure 1, shows in perspective view such a trunk placed on end and with our display attachment opened out and arranged for use. Fig. 2, is a vertical section through that part 35 of the trunk to which this attachment is connected and which part receives it when it is closed up after use. Fig. 3, in enlarged side-elevation with parts between ends broken out illustrates the construction of the display-attachment, showing also in section that portion of the trunk to which it is attached. Fig. 4, shows in intermediate position a part of the attachment illustrated in the preceding figure. Fig. 5, is an end or 40 edge-view of the upper part of Fig. 3, the attachment being in a position as shown in Fig. 2. Fig. 6, is part of a view of the lower portion of Fig. 3, and taken at right angles to said figure. Fig. 7, is a similar 45 view of an intermediate portion of said figure. Fig. 8, is an enlarged sectional view of Fig. 6, and shows details of construction.

The device consists substantially of a rod 50 upon which the articles or samples to be exhibited, whatever they may be, are sup-

ported while said rod is in a horizontal position. This rod is sustained in this position at one of its ends by the trunk and at its other end by a post 11, the connection of both of these ends being articulated to permit 60 folding up of the attachment on itself and within the trunk.

Trunks consist usually of two sections 12 and 13, hingedly connected, one serving as a lid for the other one. For use in the manner 65 intended the trunk is placed on end as shown in Fig. 1, before being opened. The attachment may be connected to either one of these trunk-sections. In the drawing it is shown connected to section 13, which may 70 be considered the lid, the connection being by rod 10 which at one of its ends is connected to this section. The connection is to one of the sides of this section, preferably the outer one designated by 14, and to the inner surface thereof. So connected, the attachment when in position as shown in Fig. 1, interferes least with access to the trunk for the purpose of handling its contents when the same is open as shown. It is also entirely 75 out of the way and forms no obstruction which will interfere with the packing of the trunk, when closed up within this latter as shown in Fig. 2.

By preference the connection is near the 80 free edge of side 14, and also near one end of the same, so as to support, with reference to positions as shown in Fig. 1, rod 10 at an elevation sufficient for the purpose. Since this elevation can never be too high at best, the 85 attachment is for obvious reasons at the upper end referring to Fig. 1 of said side. Post 11 is of course of a height which is substantially equal to the distance from the floor to the point of attachment of rod 10 to 90 side 14, so that said rod 10 may be supported in an approximately horizontal position by the trunk at one of its ends, and by post 11 at the other as shown in Fig. 1.

The connection of rod 10 to side 14 is a pivotal one, and while it might be directly to said side, it is by preference to an intermediate bracket 15, which is angularly arranged so as to permit its simultaneous attachment to side 14, and to the adjacent end 105 of the trunk, whereby the connection of said rod becomes more durable and substantial. The other end of rod 10 is directly connected to the end of post 11 by an articulated joint as shown at 16. A brace 17 is provided, pivot- 110

ally attached to one of the jointed parts. It has a slot 18 which is occupied by a headed pin 19 which projects from the other jointed part. The length of this slot limits the 5 swinging movement of the post with reference to rod 10 to the proper extent so that said post cannot swing beyond the proper supporting position, which is one at right angles to rod 10. At one of its ends this slot widens 10 out to form a notch 20, which permits the brace to slightly drop when said notch is opposite the shank of pin 19. This permits this shank to enter and occupy notch 20 whereby post 11 is locked in proper position 15 on rod 10 as shown in Figs. 1 and 3, and the two parts are stiffly braced on each other and prevented from collapsing. When the parts are to be closed up, brace 17 is slightly lifted to disengage it from pin 19, while at the same 20 time post 11 is swung inwardly on rod 10 as shown in Fig. 4. At the lower end of post 11, also connected with an articulated joint 21, there are two foot braces 22, which may 25 be turned into angular relation with reference to post 11 and so as to project in opposite directions therefrom as shown in Figs. 1 and 6. When so turned out, they project at right angles to said post and also at right angles to the plane between it and rod 10, there- 30 by bracing the opened-out attachment and preventing it from tipping laterally.

By resting against shoulders 23 at the lower end of post 11 as best shown in Fig. 6, these foot braces are prevented from turning 35 beyond the angular bracing position. When the device is to be closed up and before turned into the trunk, they are turned into alinement with post 11, as shown in Figs. 2 and 8, so as to be out of the way and to clear 40 the edge of the trunk when the attachment is turned into this latter.

Since post 11, in order to support rod 10 in approximately horizontal position, must be of sufficient length, which length is obvi- 45 ously in excess of the inside length of the trunk, it is necessary, in order to permit said post after use of the attachment to be turned into the trunk, that it be also in sections, two, *a* and *b*, being sufficient, which are connected 50 to each other by an articulated joint 24 which permits said post to be collapsed. When extended, these sections are held in alinement on each other by a spring-actuated snap-catch 25, which is attached to one of 55 the sections and adapted to engage a notch 26 in the other section. The procedure for closing up is now as follows: Catch 25 is lifted out of notch 26 and section *b* of the post is folded up against section *a* as indicated in 60 dotted lines in Fig. 1. Foot-braces 22 are straightened out. Brace 17 is lifted out of engagement with pin 19 and the doubled up post is swung against rod 10. This latter with the post is now turned into the trunk- 65 section to which it is connected, the closed

up attachment appearing then substantially as shown in Fig. 2, hanging down on the inside of the trunk. It is preferably secured in this position within the trunk by a strap 70 27, one end of which is permanently secured inside of the trunk and whereby the attachment is held immovable while the trunk is in transit.

Flopping of the foot-braces is avoided by preventing them from working too freely at 75 their joint, for which purpose a friction spring 28 is used and applied as shown in Fig. 8.

The jointed connections of rod 10 and of post 11 are such that the sections of the post and rod 10, when being closed up, swing all 80 in one plane, and parallel to the trunk-side to which the attachment is connected. The parts, when closed up, are thus caused to lie close to this side, where they are out of the 85 way and do not take up much space, nor interfere with the packing of the trunk or obstruct access to it.

Along the edges of the trunk-sections there extend usually inwardly extending cleats, or strips as shown at 29 in Fig. 3, 90 which form part of the trunk-structure and serve for various purposes.

The attachment in order to clear the strip at the front-edge of the side 14 while being moved in or out of the trunk, must be connected accordingly, that is it must be supported with sufficient space between it and the side of the trunk to which it is attached. For such purpose that part of attaching 95 bracket 15, to which the end of rod 10 is piv- 100 oted, is shaped to extend away from side 14, a distance sufficient for the purpose and as best shown at C in Fig. 5, these projecting cleats being indicated therein in dotted lines. The attachment may thus swing freely in 105 and out of the trunk without interfering with any parts which may project inwardly from the trunk side to which the attachment is connected.

Having described our invention, we claim 110 as new:

1. A collapsible display-attachment for trunks adjustably connected to one of the sides of a trunk to permit it to be erected in supporting position outside of the trunk, or 115 collapsed so as to be inside of the same and lie close against the side to which the attachment is connected so as not to interfere with access to the trunk.

2. In a trunk, the combination of a 120 bracket, shaped to permit it to be connected to two sides of the trunk, a sample-supporting rod adjustably connected to this bracket and means to sustain the same in sample-supporting position outside of the trunk. 125

3. A collapsible display-attachment for trunks adapted to be adjusted to positions either outside of the trunk, or folded up within this latter, the same consisting of a supporting rod hingedly connected at one of its 130

ends to one of the sides of the trunk, and a post hingedly connected to the other end of this rod, the connection of these parts being such that the post folds up on the rod and both fold up in a plane parallel to the side to which the rod is connected.

4. A collapsible display-attachment for trunks adapted to be adjusted to a position outside of the trunk, it consisting of a supporting rod connected at one of its ends within the trunk, a post connected at one of its ends to the other end of this rod and foot-braces at the other end of this post, the connection of these latter to the post being a hinged one so as to permit their alinement with said post and the connection of this latter and of the rod being such that they may be folded up on each other and closed into the trunk.

5. A collapsible display-attachment for trunks adapted to be adjusted to a position outside of the trunk, it consisting of a supporting rod connected at one of its ends within the trunk, a post comprising two jointed-sections connected at the end of one of its sections to the other end of the rod, and means to lock these post-sections in alinement, the connection of the rod, post and the sections of this latter being such as to permit them to be folded up on each other and closed into the trunk.

6. A collapsible display-attachment for trunks adapted to be adjusted to positions, either outside of the trunk, or folded up within this latter, the same consisting of a supporting rod hingedly connected at one of its ends to one of the sides of the trunk and a post hingedly connected to the other end of this rod, the connection of these parts being such that when folded up, they move in a plane parallel to the side to which the attachment is connected and means to hold the folded up attachment against the inside of the trunk.

7. A collapsible display-attachment for trunks consisting of a rod and of a post both hingedly connected to each other and one of them hingedly connected to the trunk so that the attachment may be folded up and closed into the trunk, or adjusted to supporting position outside of this latter, in which position rod and post are arranged at right angles to each other, a brace having a slot with a notch at one of its ends secured to one of these members and a pin projecting from the other member and fitted to occupy the slot in the brace whereby the adjustment of rod and post is limited to supporting position and whereby, when said pin occupies the notch mentioned, which latter is accordingly located, rod and post are locked in such supporting position.

8. In a display attachment for trunks, the combination of a post, a supporting rod hingedly connected at one of its ends to one end of this post and a trunk to which the other end of the supporting rod is connected, this latter connection being to the inside of one of the sides of the trunk, so that, when the attachment is folded up, it lies close to such side and does not obstruct access to the trunk.

9. In a display-attachment for trunks, the combination of a post consisting of two sections hingedly connected to each other, a supporting rod to one end of which one end of one of the post-sections is hinged and a trunk to which the other end of the supporting rod is hinged.

In testimony whereof we hereunto affix our signatures in the presence of two witnesses.
